UNITED STATES PATENT OFFICE.

BELTON TATTNALL HAMILTON, OF LONDON, ENGLAND.

GUN-MOUNTING.

1,300,264.

Specification of Letters Patent. Patented Apr. 15, 1919.

Application filed February 27, 1919. Serial No. 279,587.

To all whom it may concern:

Be it known that I, BELTON TATTNALL HAMILTON, major R. A. F., a subject of the King of England, and resident of London, England, have invented certain new and useful Improvements in Gun-Mountings, of which the following is a specification.

This invention relates to gun mountings for non-recoil guns, as for instance of the 10 Davis type, and has for its object to prevent the gunner from inadvertently laying the gun in such a position that structures adjacent to the gun may be damaged by the rear shot or blast. The mounting is more 15 particularly intended for use on aircraft.

According to this invention the gun is carried by horizontal trunnions on a crosshead which is rotatable on a fixed vertical pivot and on the upper end of this pivot is fixed a 20 member which is formed with one or more cam-shaped projecting parts. The gun carries a lever which is downwardly directed so as to bear on the projecting part or parts of the fixed member whereby the elevation 25 or depression of the gun will be limited for certain positions of the gun about the vertical pivot as determined by the formation of the fixed member. A substantially circular plate is fixed below the crosshead and 30 provided at or near its periphery with notches or projections which are relatively positioned to correspond with the relative positions of the extremities of the cam-shaped part or parts carried by the pivot. 35 A catch adapted to engage the periphery of this plate is carried by the crosshead in a position which bears the same relation to the arc between the notches or projections as the position of the lever which projects down- 40 wardly from the gun bears to the extremities of the cam-shaped part or parts. In one construction a single cam member projects laterally from the upper end of the fixed pivot and the periphery of the circular 45 fixed plate below the crosshead is cut away throughout an arc which is equal to and coincides with the arc of the fixed projection.

While this reduced portion is engaged by a catch carried by the crosshead, the engagement of these parts serves to limit the arc through which the gun can be trained when it has been so turned about the pivot that the gun lever is in operative engagement with the projecting cam. In another 55 construction the pivot is provided with two cam-shaped members which project laterally

with a transverse slot or passage between them. The lever carried by the gun is of such a width as will allow it to pass freely through this passage when the gun has been 60 turned about the pivot so as to bring the lever into coincidence with the passage.

The accompanying drawings illustrate by way of example two alternative constructions which may be adopted in putting the 65 invention into practice. In these drawings:—

Figure 1 is a perspective view showing one construction.

Fig. 2 shows diagrammatically in plan the 70 circular plate and catch on the crosshead.

Fig. 3 is a side elevation of another construction.

Fig. 4 is a front view of the same.

Like letters indicate like parts throughout the drawings.

Referring to Fig. 1 the mounting comprises a crosshead A which carries in bearings A' the trunnions of the gun B. The crosshead is rotatable on a vertical pivot C 80 which is fixed in some convenient manner on the aircraft or elsewhere as required.

The pivot C projects through the center of the crosshead and has fixed upon its upper extremity an arc-shaped cam D. Rig- 85 idly attached to the gun and centrally below the trunnion axis is a downwardly projecting lever E which when the gun is given a certain degree of elevation or depression as the case may be will bear on or engage 90 the periphery of the cam D. As shown in Fig. 1 the cam is arranged and shaped to insure safety for a Davis gun mounted on the prow or nose of a twin tractor or a pusher biplane. The contour of the cam D 95 is designed so that the axis of the gun, if prolonged to the rear, is prevented from passing nearer than 3 feet above the leading edge of the top plane during training, until such degree is reached that the pro- 100 longed axis of the gun is 3 feet in advance of the leading wing tip. At this point the cam is cut away so that the gun may then be further elevated to any extent desirable. Various shapes or contours of cams may be 105 used according to conditions of design of the aircraft upon which the gun is mounted.

The pivot C upon which the crosshead A turns has fixed to it below the crosshead socket a plate F having a part F' cut away 110 so forming stops or projections F² in its periphery. A member G having a pin or

5 catch G' is mounted on the crosshead and controlled by a spring G^2 so that the pin G' normally engages with the part F' in such a manner that the permissible degree of training of the gun is limited by the catch coming into contact with one or other of the projecting stops F^2 .

10 The position of these stops and the length of the arc F' is decided by the conditions of design of the aircraft to keep the gun during training in safe firing positions. In this case the arc F' coincides with and is equal to the arc of the laterally projecting cam D . The catch G' is arranged to be withdrawn by hand against the action of the spring G^2 so that the gun may be moved beyond the projections F^2 when desired. Thus by means of the engagement of the lever on the gun with the periphery of the cam D 15 and the engagement of the catch G' on the crosshead A with the projections F^2 on the plate F , limiting stops are provided which according to their disposition restrict the movements of the gun within safe limits or 20 zones of fire.

25 In the modified construction shown in Figs. 3 and 4 the cam comprises two cam-shaped parts DD' between which is a transverse passage or slot D^2 . In this case the cam parts DD' are formed of similar dimensions and shape but if required they may be dissimilar and the slot D^2 may be otherwise than with parallel sides as in the arrangement here shown. The dimensions of 30 the lever E carried by the gun are such that it will bear on the peripheries of the cams DD' until the gun has been turned about the pivot C so as to bring the lever E into coincidence with the passage D^2 when the lever 35 can pass freely through this passage. The gun can then be elevated or depressed without restriction so long as it is not trained beyond the arc or arcs determined by the width of the passage D^2 . The turning of 40 the gun about the pivot C is limited accordingly by the engagement of the catch G with a notch or recess F' formed in the periphery of the fixed circular plate F . Two such notches may be provided and oppositely arranged in the plate F so as to correspond with the opposite ends of the passage D^2 .

45 In some cases two levers such as E may be fixed on the gun one projecting toward the front and the other toward the rear so as to engage opposite parts of projecting cams such as DD' . One of these levers will restrict the degree of depression and the other the elevation of the gun. In the construction illustrated in Figs. 3 and 4 the lever E and cam parts DD' may be so formed that while the gun can be restricted in elevation so long as the lever lies to one side of the axis of the pivot C on the other hand if the lever be passed through the 50 slot D^2 and brought to the other side of the

55 pivot axis the lever when in contact with the cam parts will cause the gun to be restricted in depression.

60 The details of construction may be modified as desired to suit the position in which the gun is to be disposed and the manner of its use.

65 What I claim as new and desire to secure by Letters Patent is:—

70 1. In a mounting for a gun of the non-recoil type the combination of a fixed vertical pivot, a crosshead rotatably mounted thereon, a gun mounted in said crosshead so as to be capable of elevation and depression, a cam member secured to the pivot and 75 a lever mounted on the gun and co-operating with the cam member to limit the elevation and depression of the gun.

80 2. In a mounting for a gun of the non-recoil type the combination of a fixed vertical pivot, a crosshead rotatably mounted thereon, a gun mounted in said crosshead so as to be capable of elevation and depression, a cam member secured to the pivot, 85 a lever mounted on the gun and co-operating with the cam member to limit the elevation and depression of the gun, and means adapted to limit the rotation of the crosshead about the pivot as set forth.

90 3. In a mounting for a gun of the non-recoil type the combination of a fixed vertical pivot, a crosshead rotatably mounted thereon, a gun mounted in the crosshead so as to be capable of elevation and depression, a cam member secured to the pivot, a lever mounted on the gun and co-operating with the cam member to limit the elevation and depression of the gun, and means adapted to limit the horizontal movement of the crosshead about the pivot, said limited horizontal movement coinciding with the position in which the lever on the gun is in operative engagement with the cam member as set forth.

95 4. In a mounting for a gun of the non-recoil type the combination of a fixed vertical pivot, a crosshead rotatably mounted thereon, a gun mounted in the crosshead so as to be capable of elevation and depression, a cam member secured to the upper 100 end of the pivot, a lever mounted on the gun and co-operating with the cam member to limit the elevation and depression of the gun, a plate secured to the pivot below the crosshead, a member carried by the crosshead and co-operating with the plate to restrict the arc through which the crosshead and gun can be turned about the pivot and means for disengaging said member from the plate as set forth.

105 5. In a mounting for a gun of the non-recoil type the combination of a fixed vertical pivot, a crosshead rotatably mounted thereon, a gun mounted in the crosshead so as to be capable of elevation and depression,

a cam member secured to the upper end of the pivot, a lever mounted on the gun and coöperating with the cam member to limit the elevation and depression of the gun, a 5 plate secured to the pivot below the cross-head, a spring controlled member carried by the crosshead and coöperating with the plate to restrict the arc through which the crosshead and gun can be turned about the

pivot this restricted arc coinciding with the 10 position in which the lever is in operative engagement with the cam member, and means for disengaging the spring controlled member from the plate as set forth.

In testimony whereof I have signed my 15 name to this specification.

BELTON TATTNALL HAMILTON.
